MACHINE FOR MAKING REINFORCED WEBS

Chester E. Claff and Carl A. Moeller, Randolph, Mass., assignors, by mesne assignments, to M. B. Claff & Sons, Inc., Randolph, Mass., a corporation of Massachusetts

Original application June 6, 1947, Serial No. 752,980; now Patent No. 2,646,914, dated July 28, 1953. Divided and this application April 26, 1950, Serial No. 158,156.

7 Claims. (Cl. 154—1.7)

1

The present invention relates to the manufacture of boxes or cartons from pasteboard or the like, and more particularly to machines for producing reinforced webs from which blanks may be made for such boxes or cartons.

Some types of boxes or cartons, such, for example, as boxes in which shoes are customarily packed and stored on the shelves of the retail dealer, are subjected in use to excessive strain at the corners, due to the common practice of shoe salesmen of drawing the box outwardly from the store shelf, and often from beneath other boxes stacked above, by inserting one or more fingers downwardly within the box or upwardly within the cover, and pulling against the front wall of the box or cover. This puts a heavy strain on the front top corners of the box or the bottom front corners of the cover, with the result that the boxes and covers are frequently torn at one or both front corners.

It is the object of the present invention to provide a machine for producing webs of pasteboard or the like having a reinforcing cord or string secured along one or both edges thereof, from which webs reinforced blanks may be formed which are suitable for use in making boxes and box covers having string reinforcement at their top and bottom corners, respectively.

With this object in view, the present invention consists in a machine for applying and securing a reinforcing string or cord to the edges of the web of cardboard or the like to form a reinforced web from which individual box blanks may be produced.

Preferably the opposite edges of the web of box material are cut or split inwardly a short distance to form a cleft or seat to receive the cord to which adhesive has been applied, and a cover paper is adhesively secured to the opposite marginal surfaces of the web, passing tightly around the cord seated in the cleft. If desired, however, the splitting of the edge of the web may be omitted and the adhesively coated cord applied directly to the unsplit edge with cover paper passing around the cord and secured to the opposite margins of the web.

In the accompanying drawings, which illustrate more or less diagrammatically the present invention, Fig. 1 is a top plan view and Fig. 2 is a side elevation of the machine for slitting the edges of the web of box blank material and laying the reinforcing cord in the slit thus formed, and applying the web of cover paper to one face of the cardboard web, and for folding the same over and around the cord and onto the

2

opposite face of the cardboard to provide a composite web of cardboard, reinforcing cord and cover paper preparatory to the forming of individual blanks therefrom; Fig. 3 is a vertical, transverse, section on line 3—3 of Fig. 2, showing a portion of a slitting knife for slitting the edge of the pasteboard web as it advances between the top and bottom plates or supports; Fig. 4 is a vertical, transverse, sectional view taken on line 4—4 of Fig. 2, showing a portion of the cord-guiding roll laying the cord in the cleft in the margin of the pasteboard web; Fig. 5 is a vertical transverse, sectional view on line 5—5 of Fig. 2, showing a side margin of the pasteboard web with the cord positioned in the cleft and the cover paper applied to the lower face of the cardboard web and extending marginally therefrom, preparatory to being folded around the edge of the pasteboard and cord and onto the top face of the cardboard; Fig. 6 is a transverse sectional view of the cardboard web, reinforcing string and cover paper in final assembled position; Fig. 7 is a sectional view of a modification of the invention in which the adhesively coated cord is applied directly to the edge of the unsplit pasteboard web, and Fig. 8 shows in section the cover paper on the lower face of such web and wrapped around the cord and secured to the top marginal face; Fig. 9 is a perspective of the finished blank suitable for a box cover, and Fig. 10 is a similar view of a cover shown upside down formed from the blank of Fig. 9; Fig. 11 is a perspective view, partly in section and on an enlarged scale, of a corner of the box cover, still upside down, with the side and bottom cut away to show the internal construction.

In the machine of Figs. 1 and 2, the web of cardboard 15 is supplied from a roll 17, from which it is drawn by the power driven feed rolls 18. From the feed rolls the web passes through the edge guides 21, which guide and align the web preparatory to the edge slitting operation which is performed by the circular slitting knives 23 on the vertical rotating shafts 25.

In order to present the web properly to the edge slitting knives, stationary guides are provided in the form of a lower support 26 and a top plate 27 between which the web passes. The inner adjacent faces 28 of these guides are beveled at their outer edges as shown in Fig. 3, to accommodate the beveled edges 29 of the slitting knives, and permit the latter to spread open the slit to provide a groove or seat for the cord.

The cords 30 are fed from a supply cop or roll 31 past the adhesive applying roll 33, where they

are coated with glue or other suitable adhesive supplied from the tank 35 and transfer roll 37. The cord-applying roll 38 has a grooved periphery 39 to receive the cord from the roll 33, and guides and presses the cord into the cleft or slit 41 in the edge of the web 15, the latter at such time passing between the top guide 43 and bottom support 45.

The web 15 with glue-coated cord 30 embedded in the slits on each edge thereof next passes to the rolls 47 where the cover paper 49 from the roll 51 is applied to the bottom face of the cardboard web 15. The top face of the cover paper on its way from the supply 51 is coated by the pasting roll 57 with paste received from the transfer roll 59 and paste reservoir 61. The web 49 of cover paper is wider than the web 15 of pasteboard, so that when the cover paper is applied to the bottom face of the web of pasteboard, there is a projecting margin 63 of cover paper on each side of the pasteboard web, as shown in Figs. 1 and 5.

The combined pasteboard and cover paper webs then pass to the plows 65, shaped to turn over the projecting margins 63 of the cover paper around the edge of the cardboard and reinforcing cord and onto the top marginal surface of the cardboard, as shown in Fig. 6.

From the plows the composite web passes between the pressure and feed rolls 67 which press the parts forcibly together, at the same time advancing the web to the conventional creasing, slitting, and severing mechanisms for producing blanks of conventional form such as shown in Fig. 9.

This blank comprises the main or body portion 69, side wings 71, and end wings 73 with the end wing extensions 75. Longitudinal creases or fold lines 77 are positioned between the side wings 71 and the body 69, and transverse fold lines 79 separate the end wings 73 from the body 69 and extend onto the side wings to separate the side wing extensions or corner tabs 81 from the side wings. Supplementary transverse creases 83 lie between the end wings 73 and extensions 75.

The reinforcing cord 30 is shown in dotted outline at the outer edges of the side wings 71, with the cover paper 63 wrapped around the edges of the cord, and extending inwardly on the face of the side wings. Slots or notches 85 are provided at the ends of the blank, which separate the corner tabs 81 from the end wings 73 and extensions 75.

The blank shown in Fig. 9 is a box cover blank from which the box cover shown in Fig. 10 will be formed or "set up," with the side wings 71 turned up onto the sides and the corner tabs 81 turned inwardly to form a portion of the end construction. The end wings 73 are turned up and secured by glue or adhesive to the turned-in corner tabs 81, and the end wing extensions 75 turned inwardly and downwardly and secured by adhesive to the inner faces of the corner tabs and the end wings.

As shown in enlarged detail in Fig. 11, the reinforcing cord 30 lies along the top edges of the side wings and corner tabs being firmly secured in the cleft or slit by adhesive and the cover paper 63.

When the box is drawn forward by the shoe salesman by his fingers inserted behind the front end of the cover, the strain on the corners of the cover will be taken largely by the reinforcing cord, and tearing or breaking of the cover and box board at such times will be prevented.

While the present invention has been shown and described as embodied in a machine for producing a reinforced web particularly designed and intended for use in making box blanks for pasteboard shoe boxes and the like with a cover paper which also serves as a binder to bind or secure the reinforcing cord to the edge of the web, it is not to be limited thereto but may be embodied in machines for making reinforced webs from web material other than pasteboard, and securing or binding materials other than cover paper, such reinforced web being intended for other uses than the manufacture of boxes or cartons.

15 Nor is the invention to be limited to the specific forms and arrangement of parts herein shown and described, but may be embodied in other forms and arrangements within the scope of the language of the appended claims.

20 Where in the foregoing description reference is made to a box or boxes, this is to be understood as including box covers.

25 This application is a division of our pending application filed June 6, 1947, Serial No. 752,980, now Patent No. 2,646,914.

Having thus described the invention, what is claimed is:

1. A machine for making a reinforced web having, in combination, means for supplying web material, a rotary knife for slitting the edge of the web inwardly, flaring means engaging the edge margins of the web to support the web adjacent the slitting knife and permit a limited depth of the slit, devices for supplying a reinforcing cord, and a guide roll having a grooved cord-receiving face for guiding and pressing the cord into the slit in the edge of the web.

2. A machine for making a reinforced web having, in combination, means for supplying web material, a rotary slitting knife for slitting the edge of the web inwardly, an edge guide for guiding the web past the slitting knife, devices for supplying a reinforcing cord, a guide roll having a grooved, cord-receiving face for guiding and pressing the cord into the slit in the edge of the web, and an edge guide for guiding the web adjacent the guide roll, said edge guide comprising a pair of web engaging members spaced from one another to receive the web therebetween, the inner faces of said members being outwardly beveled to permit a limited separation of the margins of the web adjacent the slit during the cord applying operation to position the cord at the edge of the web.

3. A machine for making a reinforced web having, in combination, means for supplying web material, a pair of rotary slitting knives with wedge-shaped peripheries for slitting opposite edges of the web inwardly and spreading apart the edge portions of the web adjacent the slit, edge guides for supporting the edges of the web, said guides being provided with outwardly flaring web-engaging faces for supporting and positioning the edges of the web as it passes the slitting knives to permit a limited spreading apart of the said edge portions, devices for supplying reinforcing cords, and a pair of guide rolls each having a grooved cord-receiving face for guiding and pressing the cords into the slits in the edges of the web and positioning the cords at the edges of the web.

4. A machine for making a reinforced web having, in combination, guiding means for the web, means for advancing web material through the web guiding means, slitting means positioned adjacent the web guiding means for slitting the

edge of the web inwardly, means for supplying a reinforcing cord, and cord guiding means for directing the cord into the slit in the edge of the web, the web guiding means in the region of cord introduction having spaced wall portions engaging and supporting the edge margins of the web, the wall spacing at the margin of the web corresponding substantially to the total thickness of the web and cord and the wall spacing inwardly of the margin corresponding substantially to the web thickness, whereby the cord is positioned at the edge of the web.

5. A machine for making a reinforced web having, in combination, means for supplying web material, web guiding means having spaced surfaces between which the web is advanced, means for advancing the web through the web guiding means, slitting means positioned adjacent the web guiding means for slitting the edge of the web inwardly, means for supplying a reinforcing cord, and cord guiding means for directing the cord into the slit in the edge of the web, the web guiding means in the vicinity of the cord guiding means having flared surfaces adjacent the edge margins of the web to support the slit portions and limit the opening thereof substantially to the thickness of the cord and thereby to position the cord at the edge of the web.

6. A machine for making a reinforced web having, in combination, means for supplying web material, guiding means having spaced surfaces between which the web is advanced, means for advancing the web through the web guiding means, slitting means positioned adjacent the guiding means for slitting the edge of the web inwardly, means for supplying a reinforcing cord, means for applying adhesive to the cord, and grooved cord guiding means for directing the adhesively coated cord into the slit in the web edge, the web guiding means in the vicinity of the grooved cord guide having spaced guide surfaces to engage and support the split edges of the web, the spacing of said guide surfaces at the web edge corresponding substantially to the total thick-

ness of web and cord, said guide surfaces inwardly adjacent the web edge having a spacing corresponding substantially to the web thickness, thereby to limit the slit opening at the web edge substantially to the cord thickness for positioning the cord at said edge.

7. A machine for making a reinforced web having, in combination, means for supplying web material, guiding means having spaced surfaces between which the web is advanced, means for advancing the web through the web guiding means, slitting means positioned adjacent the guiding means for slitting the edge of the web inwardly, means for supplying a reinforcing cord, means for applying adhesive to the cord, grooved cord guiding means for directing the adhesively coated cord into the slit in the web edge, the web guiding means in the vicinity of the grooved cord guide having spaced guide surfaces to engage and support the split edges of the web, the spacing of said guide surfaces at the web edge corresponding substantially to the total thickness of web and cord, said guide surfaces inwardly adjacent the web edge having a spacing corresponding substantially to the web thickness, thereby to limit the slit opening at the web edge substantially to the cord thickness for positioning the cord at said edge, means for supplying adhesively coated paper, and means for applying said paper to one face of the web, around the slit edge in contact with the cord in the slit, and onto the other face of the web.
